UNITED STATES PATENT OFFICE.

CHARLES GIBBS, OF NEW YORK, N. Y., ASSIGNOR TO UNDERWOOD TYPEWRITER COMPANY, OF NEW YORK, N. Y., A CORPORATION OF DELAWARE.

STENCILING-MACHINE.

1,094,713.

Specification of Letters Patent.

Patented Apr. 28, 1914.

Application filed July 12, 1911. Serial No. 638,048.

To all whom it may concern:

Be it known that I, CHARLES GIBBS, a citizen of the United States, residing in borough of Bronx, city of New York, in the county of New York and State of New York, have invented certain new and useful Improvements in Stenciling-Machines, of which the following is a specification.

This invention relates to sheet feeding devices for stenciling machines, etc., and is in the nature of an improvement upon the invention disclosed in application No. 516,854, filed September 9, 1909. In said application, the sheet pile is placed upon a table and is set to gages. The leading edges of the sheets are held by clips, and a pressure bar bears down upon the rear ends of the sheets. A feed roll and controlling mechanism therefore depend from a carriage, which reciprocates on the table toward and away from the stencil cylinder. Said roll makes a complete reciprocation at each revolution of said cylinder. The roll turns freely for the first part of its backward stroke and for the rest of the stroke is clutched or prevented from turning by said controlling mechanism and downward pressure is simultaneously applied upon the roll or rolls whereby the top sheet is buckled up from the pile, and its leading edge withdrawn from said clip. Then the roll is maintained clutched against rotation during its entire forward stroke by said mechanism so that the separated top sheet, having its rear edge dragged thereby out from beneath said pressure bar, is advanced into the bite of said cylinder and its pressure roll for stenciling or printing.

One of the principal objects of my invention is to provide simplified inexpensive and improved mechanism for reciprocating said carriage.

Another important object of the present invention is to provide a feeding mechanism that can be readily and conveniently connected to and disconnected from the stenciling machine to convert it from a hand fed to a power-fed machine.

Another object is to provide means for interchanging the feed rolls, so that either

wheels having pointed teeth or pickers, or other wheels or rolls, may be used, and the spacing between them conveniently changed.

A further object is to make improved provision for adjusting the end gage with the pressure bar thereon, toward and away from the clips and stencil cylinder to fit different lengths of sheets.

In the preferred form of this invention, the feeding machine is independent, that is, it does not form a part of the stenciling machine, and the forward end of its frame hooks on to the stenciling or printing machine frame by means of pins, whereby both machine frames are locked together. A drive shaft on the feeding machine for the mechanism that reciprocates the carriage, is clutched to a shaft on the stenciling machine, which is driven from the stencil cylinder drive shaft, which may be either hand or power driven, so that the feeding machine operates in unison with said cylinder. Said feeding machine drive shaft extends from front to rear of the machine near the underside of the table and preferably close to the side of the frame. This shaft is geared to another shaft, which is in turn geared to a crank that revolves in a horizontal plane near the underside of the table, midway between the sides of the machine. The carriage, which comprises a bar close to the underside of the table and uprights extending therefrom, has a slide block fixed on said bar midway, which slides on a guide bar disposed centrally from front to rear of the machine. A pitman connects said crank with the slide block whereby the carriage is reciprocated.

To detach the feeding machine from the printing machine, it is merely required to unhook the frames and unlock the shaft clutch. An ordinary feed table may then be hooked on, thus rendering the printing machine hand or machine fed readily and conveniently.

The guiding of the carriage midway between its sides secures against binding thereof, and the operation of the crank and pitman in a horizontal plane close to the under-

side of the table together with the shaft 1 of Fig. 9. Fig. 11 shows a detail of 65 drive provided for the crank results in light, the feed roll clutching mechanism. compact and effective mechanism which renders the feeding machine portable thereby 5 aiding greatly in attaching and detaching the feeding machine.

The feed roll shaft is entirely supported upon the arm that carries the clutching mechanism leaving the ends thereof free. A 10 sleeve with the clutch wheel or disk thereon is journaled on said arm and the shaft slides therein. Feed rolls or toothed wheels may then be placed on the shaft and spaced as desired with collars and then tightened 15 to the sleeve by threading a nut on each end of the shaft. By unscrewing said nuts different feed rolls or wheels can be interchanged and their spacing changed to suit different feeding requirements. The end 20 gage is adjusted by its bolt passing through a slot in the table, whereby the gage may be moved toward and away from the printing cylinder and tightened in position, to fit different lengths of sheets. Clutching of 25 the shafts is accomplished by a sleeve splined on one of the shafts sliding over the other, on which a projection engages with a slot on the sleeve, whereby the shafts are clutched. A spring presses against said 30 sleeve to maintain the shafts clutched and a locking member upon the sleeve engages with the machine frame to overcome the effect of said spring when the clutch is unlocked to prevent the sleeve from being 35 pressed outward.

Other objects and advantages will herein-after appear.

In the accompanying drawings, Figure 1 is a general perspective view of the machine 40 showing some of these improvements, with the carriage and feed rolls at the end of the forward stroke. Fig. 2 is a bottom plan of the machine and shows the mechanism for reciprocating the carriage. Fig. 3 is a 45 sectional side elevation of the machine showing the carriage and feed rolls at the end of the forward stroke. Fig. 4 is a sectional side elevation of a part of the machine, and shows the feed rolls clutched and buckling 50 the top sheet at the end of the backward stroke. Fig. 5 is a front elevation of the feeding machine. Fig. 6 is a side elevation of the machine and shows the carriage at the end of the forward stroke with the feed 55 rolls raised for inserting the sheets. Fig. 7 is a front elevation of the stenciling machine, partly sectional, showing the drive shaft connection for driving the feeding machine. Fig. 8 is a full size sectional view 60 of the feed roll shaft, with the clutching mechanism therefor shown in plan. Fig. 9 shows a section of the clutch that couples and uncouples the shaft that drives the feeding machine. Fig. 10 is a cross section

of Fig. 9. Fig. 11 shows a detail of 65 the feed roll clutching mechanism. The stenciling machine 1 is the well known Underwood revolving duplicator; wherein a stencil cylinder 2 may be rotated by a handle 3 or may be power driven from 70 the drive shaft 4, and a pressure roll 5 presses the sheets to be stenciled, against the cylinder. The sheet pile 6 to be stenciled is placed on the table 7 of the feeding machine, and is lined in by the side gages 8 and end 75 gage 9. Feed rolls or wheels 10 advance the sheets singly into the bite of the cylinder 2 and roll 5. Said feed rolls depend from a carriage 11 which comprises a horizontal band 12 underneath the table 7, bent upward 80 to form upright supports 13, which pass through slots 14 of said table. A slide block 15 fixed midway on portion 12 of the carriage, Fig. 2, travels on a central guide bar 16, which is close to the underside of the 85 table and is fixed at 17 and 18, whereby the carriage can be moved freely without binding.

To reciprocate the carriage, a bevel gear 19, Figs. 6 and 7, on the cylinder 2 meshes 90 with a gear 20 to rotate an upright shaft 21, which rotates, by means of bevel gears 22, a horizontal shaft 23 and the feeding machine drive shaft 24 which are clutched or coupled. Said shaft 24 extends from front 95 to rear of the feeding machine underneath table 7 and transmits its rotation to a shaft 25, by bevel gears 26, which revolve the crank 27 in a horizontal plane close to the underside of the table 7, by means of bevel 100 gears 28. The crank and slide block 15 are joined by a pitman 29, whereby the carriage 11 is reciprocated in unison with the stencil cylinder 2; said carriage receiving one complete reciprocation at each revolution of the 105 stencil cylinder.

Said feed rolls are tight on a shaft 30, which is constructed in sections as will be seen further, so that they constitute one roll or wheel 10 for feeding the sheets. The 110 shaft 30 is journaled midway upon an arm 31 which depends from a rock shaft 32 on the carriage. During the forward stroke of said feed roll it is held against rotation, to grip the top sheet from off the pile 6, and 115 advance it into the bite of the cylinder 2 and roll 5. A ball 33 is pressed by a spring 34 into the bite of an abutment 35 on an arm 31 and a wheel or disk 36 fixed on shaft 30, whereby the feed roll is prevented from 120 turning when moving forward to feed the sheets; although the roll 10 can turn freely on its backward stroke, as the periphery of wheel 36 then drives the ball 33 away from the narrowing throat formed by said periphery and abutment 35.

In order that the feed roll may be prevented from turning at the latter part of

its backward stroke to buckle the top sheet for separating it from the pile to advance it forward, an opposite ball 37, spring 38 and abutment 39 are provided, but which are 5 kept out of play by a releasing mechanism to allow the feed roll to turn freely during the first part of the backward stroke. Said releasing mechanism comprises an arm 40 normally pushing the ball 37 out of the bite, so 10 that wheel 36 and the feed roll are released for rotation. Said arm 40 is caused to push the ball by a link 41 pivoted thereto having its other end engaging the rock shaft 32, and a cam 42 upon a rock shaft 43 on the 15 carriage, engaging the link head 41^a to pull the link. An arm 44 fixed on shaft 43 has a projecting pin 45, in the path of which is a stop 46 on table 7, whereby the pin is engaged to actuate the arm 44 to turn the rock 20 shaft 43 to actuate the cam 42 for releasing the roll at the end of the forward stroke. Before reaching the latter part of the backward stroke, the pin 45 strikes an opposite stop 46^a, whereby the cam 42 is actuated to 25 disengage the link 41, which being thus released allows the spring 41^b upon arm 31 to turn the arm 40 about its fulcrum 40^a to remove its pressure from the ball 37. The 30 pressure on the ball being removed, further rotation of the feed roll is prevented till the end of the stroke. The roll being thus clutched, the top sheet is buckled as shown in Fig. 4, which removes its leading edge from clips 47, and the roll then carries the 35 sheet forward to the stenciling machine; the rear edge of the sheet being readily released from the pressure bar 48 provided on the end gage 9.

Downward pressure is temporarily applied upon the feeding rolls by a draw spring 49 which connects said roll carrying arm 31 with an arm 50 fixed to a rock shaft 51, mounted on the upright 13. This rock shaft carries a cam or arm 52 in the path of 45 a stationary adjustable stop 53 provided on table 7. Said stop engages this cam during the time that the sheet is buckled, and hence turns the rock shaft 51 to draw spring 49 to press down the feed roll for securing a 50 firmer grip on the top sheet to facilitate the buckling or picking up thereof from the sheet pile 6.

The feed roll shaft 30 is constructed to provide means for readily interchanging rolls or wheels, so that either rubber rolls or toothed wheels may be used and their spacing conveniently changed to suit different requirements in feeding, such as different grades of sheets, or differences of weather 55 making a different grip of the sheets preferable.

The construction of the shaft, shown in Fig. 8, comprises a threaded sleeve 54 which holds the clutch wheel or disk 36. A bush-

ing 55 on each side of this wheel is fitted in 65 a bearing 56 of the roll carrying arm 31, and a tapped sleeve 57 threads over sleeve 54 on each side of said bushing and is tightened thereagainst, whereby said wheel 36, sleeve 54, bushings 55, and sleeves 57 are held together for rotation. The shaft 30 slides into said sleeves, and various feed wheels or rolls 10 may be placed thereover and spaced as required by space collars or fillers 58 to suit different conditions of feeding. A nut 59 70 threads over each end of the shaft 30, and is tightened against the collar 58 which grips the shaft 30, rolls 10, and collars 58 with the sleeves 57 for rotation. It will be seen that the shaft 30 being supported entirely by the 75 arm 31 midway, leaving the ends thereof free, enables to use rolls or wheels interchangeably and to change the spacing between them, by merely unscrewing the nuts 59. A gravity latch 31^a is pivoted on the 80 feed roll arm 31 to hold the rolls up, for convenience in inserting the sheet pile, said latch catching on the rock shaft 51 when the rolls are lifted, as shown in Fig. 6. The clips 47, forming part of gage rods 60 which 85 are guided vertically by slots 61 and screws 62, bear down on the leading edges of the sheets by their own weight; and for convenience in inserting the sheet pile said clips may be maintained raised by turning the 90 handle 63, Fig. 6, of a rock shaft 64, Fig. 4, which causes a cam 65 thereon, having a flat portion 66, to engage with a spring 67 fixed to table 7. Arms 68 depending from rock shaft 64 bear upwardly against pins 100 69 of gage rods 60, whereby the clips 47 are raised; and said spring holding the cam turned, the clips are maintained raised until restored by turning back the handle 63 of the rock shaft 64. A pin 70, Fig. 6, prevents the handle 63 and its depending parts 105 from dropping too far. The end gage 9 with the pressure bar 48 thereon, Figs. 1 and 3, may be adjusted toward and away from the clips 47 and the stenciling machine, 110 to fit sheets of various lengths. The bolt 71 of the gage passes through a slot 72 in the table 7 so that the gage 9 may be moved toward and away from clips 47 to aline the sheet pile 6, and fixed in adjusted position 115 by tightening the thumb nut 73.

The mechanism for clutching, or coupling and uncoupling the shaft 23 on the stenciling machine and the feeding machine drive shaft 24, comprises a sleeve 74, splined on 120 shaft 24, which slides over the end of shaft 23. A slot 75 in the sleeve is thus engaged by a dog or projection 77 on shaft 23 entering therein, whereby the shafts are coupled for rotation. A coiled spring 78 on shaft 125 24 abutting against a collar 79 fixed to the shaft, presses against the sleeve 74 to maintain it over the shaft 23, thereby preventing

accidental uncoupling of the shafts. In an annular groove 80 of the sleeve 74 is seated a locking member or latch 81 which slides upon a guide bar 82, suspended from the table frame, by its hole 83 fitting thereover, so that the sleeve 74 can be shifted to couple and uncouple the shafts by means of moving said latch therealong. For preventing the sleeve 74 from sliding outward when uncoupled, a projection 84 on latch 81 is engaged with a recess 85 in the table frame, whereby the sleeve is locked against the action of spring 78. When the latch 81 is pulled away from recess 85, the spring 78 immediately acts to clutch, or couple the shafts; a lug 86 on the frame being struck by the latch 81 to prevent the sleeve from being pressed too far, and the end of the sleeve being beveled or cam faced at 87 to 10 guide the projection 77 into the slot 75 to facilitate the coupling. It will be observed that the sleeve 74 can seize the key 77 at only one point in the revolution of the shafts. Thus if the whole machine is once assembled correctly, the clutch if disconnected will not start the paper-feeding mechanism again until the stencil cylinder reaches the point where said feeding mechanism will be properly timed with reference to it. In other words, the paper-feed will feed at the right time by merely putting the feeding table in place even if the stencil cylinder be at one point of its operation and the feeding mechanism at some other. This makes the machine almost fool proof in this regard.

The feeding machine is connected or locked to the stenciling machine by a yoke 88 on each side of its frame hooking upon a coöperating pin 89 on the stenciling machine frame, and another pin 90 on each side of this frame supporting the feeding machine; connection and disconnection of the feeding machine and said pins being accomplished by tilting the rear of the machine. The machine frames being locked together, the latch 81 of the clutch mechanism may be manipulated to connect the shafts 23 and 24, and the reverse operation may be performed to detach the feeding machine.

It will be evident that the ready locking of the machine frames at 89, 90, and clutching of the shafts 23, 24, enables to attach and detach the feeding machine readily, so that an ordinary table may be hooked on 55 upon the stenciling machine to feed by hand, thereby rendering the machine hand or machine fed quickly and conveniently. The light and compact mechanism of this feeding machine aids in the ready attachment and detachment of the machine, and renders it portable. The support 91 at the rear of the machine is preferably hinged to the frame at 92, and a latch 93 on the support hooks on to a screw 94 upon the table, by

means of which said support may be folded, 65 when the machine is detached, for compactness and portability.

Variations may be resorted to within the scope of the invention, and portions of the improvements may be used without others. 70

Having thus described my invention, I claim:

1. In a sheet feeding machine for a stenciling or printing machine, the combination with a removable table for the sheets, a reciprocating carriage, and sheet feeding mechanism thereon, of a crank below said table revolving in a horizontal plane, a pitman connecting the crank to said carriage to reciprocate it, said crank and pitman being disposed midway between the sides of the feeding machine and connecting with said carriage midway, and means to operate the crank.

2. In a sheet feeding machine for a stenciling or printing machine, the combination with a removable table for the sheets, a reciprocating carriage, and sheet feeding mechanism thereon, of a slide on said carriage below the table, a guide therefor, said slide and guide disposed midway between the sides of said carriage to secure against binding thereof, a horizontally moving crank and pitman connecting with said slide to reciprocate said carriage, and means to operate the crank.

3. In a sheet feeding machine for a stenciling or printing machine, the combination with a removable table for the sheets, a reciprocating carriage, and sheet feeding mechanism thereon, of guiding means for said carriage below the table, said guiding means disposed midway between the sides of said carriage to secure against binding thereof, a horizontally moving crank and pitman for reciprocating the carriage connecting therewith midway, and means to operate the crank.

4. In a sheet feeding machine for a stenciling or printing machine, the combination with a table for the sheets, a reciprocating carriage, and sheet feeding mechanism thereon, of guiding means for said carriage below the table being disposed midway between the sides of the carriage, a crank below said table revolving in a horizontal plane, a pitman connecting said crank with the carriage to reciprocate it, and means to operate said crank.

5. In a sheet feeding machine for a stenciling or printing machine, the combination with a table for the sheets, a reciprocating carriage, and sheet feeding mechanism thereon, of a slide on said carriage below the table, a guide therefor, said slide and guide disposed midway between the sides of the carriage, a crank below said table revolving in a horizontal plane, a pitman connecting

said crank with the carriage to reciprocate it, and means to operate the crank.

6. In a sheet feeding machine for a stenciling or printing machine, the combination with a table for the sheets, a reciprocating carriage, and sheet feeding mechanism thereon, of a crank and pitman below said table to reciprocate said carriage, said crank and pitman disposed midway and connecting with the carriage midway between the sides of the carriage to secure against binding thereof, a revolute shaft extending from front to rear of the feeding machine, and an upstanding shaft on the printing machine engaging therewith to drive it, said revolute shaft being geared with said crank to operate it.

7. A sheet feeding machine for a stenciling or printing machine adapted to be readily detached for feeding the printing machine by hand, having the combination with a table for the sheets, and a reciprocating carriage with sheet feeding mechanism thereon, of a crank and pitman below the table operating in a horizontal plane, said pitman connecting with said carriage midway between its sides to reciprocate it without binding, a revolute shaft extending from front to rear of the feeding machine being driven by the printing machine to operate said crank, and a clutch on said shaft to disengage it from the printing machine for detaching the feeding machine.

8. A sheet feeding machine for a stenciling or printing machine adapted to be readily detached for feeding the printing machine by hand, having the combination with a table for the sheets, and a reciprocating carriage with sheet feeding mechanism thereon, of guiding means for said carriage below the table disposed midway between the sides of the carriage to secure against binding thereof, a crank and pitman operating in a horizontal plane connecting with the carriage midway to reciprocate it, a revolute shaft extending from front to rear of the feeding machine being driven by the printing machine to operate said crank, and a clutch on said shaft to disengage it from the printing machine for detaching the feeding machine.

9. A sheet feeding machine for a stenciling or printing machine, comprising a carriage with sheet feeding mechanism and a table for the sheets on which said carriage is reciprocated, having the combination of means for locking and unlocking the frames for detaching the feeding machine readily for feeding the printing machine by hand, a crank and pitman for reciprocating said carriage operating in a horizontal plane below the table, guides for the carriage disposed midway between its sides to move the carriage without binding, a revolute shaft

driven by the printing machine to operate 65 the crank, and means for uncoupling said shaft from the printing machine for detaching the feeding machine.

10. A sheet feeding machine for a stenciling or printing machine, comprising a carriage with sheet feeding mechanism and a table for the sheets on which said carriage is reciprocated, having the combination of means for locking and unlocking the frames, a crank and pitman for reciprocating said 70 carriage operating in a horizontal plane below the table, said pitman connecting with the carriage midway between its sides to move it without binding, a revolute shaft driven by the printing machine to operate 75 the crank, and a clutch to disengage said shaft from the printing machine, the feeding machine being detached from the printing machine to render it hand fed by unlocking said frames and said clutch. 80

11. In a sheet feeding machine for a stenciling or printing machine, the combination with a table for the sheets, mechanism thereon for feeding the sheets, clips on said table for the leading edges of the sheets, 90 and slidable rods on which said clips are fixed, of a rock shaft, arms extending from said shaft bearing against said rods to dispose said clips to inoperative position when said shaft is rocked, a cam or member on 95 said shaft, and a spring engaging therewith to maintain said clips in inoperative position; said shaft being rocked to disengage said spring to restore said clips. 85

12. In a sheet feeding machine for a stenciling or printing machine, the combination with a table for the sheets, mechanism thereon for feeding the sheets, clips on said table for the leading edges of the sheets, and vertically slidable rods on which said clips 100 are fixed, of a rock shaft, projections on said rods, arms extending from said shaft engaging with said projections to raise said clips when the shaft is rocked, a cam on said shaft having a flat portion, and a spring 105 pressing against the flat portion to maintain said clips raised and inoperative. 110

13. In a sheet feeding machine for a stenciling or printing machine, said machines comprising drive shafts adapted to readily 115 attach and detach to render the printing machine hand or machine fed, a clutch for the machine shafts, comprising a sleeve splined on one shaft, a slot in said sleeve, a dog on the opposite shaft, said sleeve sliding 120 over the opposite shaft to engage said dog with said slot to clutch the shafts.

14. In a sheet feeding machine for a stenciling or printing machine, said machines comprising drive shafts adapted to readily 125 attach and detach to render the printing machine hand or machine fed, a clutch for the machine shafts, comprising a sleeve splined

on one shaft, a slot in said sleeve, a dog on the opposite shaft, said sleeve sliding over the opposite shaft to engage said dog with said slot to clutch the shafts; the end of 5 said sleeve being beveled or cam-faced to guide said dog into said slot.

15. In a sheet feeding machine for a stenciling or printing machine, said machines comprising drive shafts adapted to readily 10 attach and detach to render the printing machine hand or machine fed, a clutch for the machine shafts, including a sleeve splined on one shaft, the opposite shaft being adapted to engage with said sleeve when 15 it slides thereover to clutch the shafts, and a spring normally bearing against said sleeve to prevent accidental back sliding thereof and to positively maintain the shafts clutched.

20. 16. In a sheet feeding machine for a stenciling or printing machine, said machines comprising drive shafts adapted to readily attach and detach to render the printing machine hand or machine fed, a clutch for 25 the machine shafts, including a sleeve splined on one shaft, the opposite shaft being adapted to engage with said sleeve when it slides thereover to clutch the shafts, a spring normally bearing against said sleeve 30 to prevent accidental back sliding thereof and to positively maintain the shafts clutched, and a member on said sleeve engaging with the machine frame or a fixed member when the clutch is unlocked to prevent 35 said spring from pressing the sleeve outward.

17. In a sheet feeding machine for a stenciling or printing machine, the combination 40 with a table for the sheets, a reciprocating carriage and sheet feeding mechanism thereon, of a shaft for carrying sheet feeding 45 rolls or wheels being supported from said carriage, and having means for readily interchanging different rolls and wheels 50 to suit varying requirements in feeding; said means including an arm for supporting the shaft midway to leave the ends thereof free, collars or fillers for spacing the wheels on the shaft, and nuts threading 55 on the shaft to grip said wheels and collars to rotate with the shaft.

18. In a sheet feeding machine for a stenciling or printing machine, the combination 55 with a table for the sheets, a reciprocating carriage, and sheet feeding mechanism thereon including feeding rolls or wheels, and clutching mechanism therefor, of a shaft for said rolls supported between its ends on an arm from the carriage to leave 60 the ends free, a threaded sleeve for said shaft, a disk on said sleeve to operate with the clutching mechanism, a bushing on each side of said disk fitting in a bearing on said arm, and a sleeve for the shaft on each side

of said bushings being tapped to thread 65 over said former sleeve and being tightened against said bushings to hold the sleeves, bushings, and disk together in said bearing; said shaft being capable to slide in and out of said sleeve; said feed rolls or wheels being 70 mounted on said shaft and spaced by collars, and a nut at each end of the shaft threading thereover and being tightened to hold the shaft, collars, and sleeves for rotating together; said rolls or wheels being 75 removable for changing wheels or spacing them by unscrewing said nuts.

19. In a sheet feeding machine for a stenciling or printing machine, the combination 80 with a table for the sheets, a reciprocating carriage, sheet feeding rolls or wheels thereon, and clutching mechanism therefor, of a shaft for said rolls supported between its ends on an arm from the carriage to leave its ends free, a sleeve journaled on said 85 arm, a disk or wheel on said sleeve to operate with said clutching mechanism, said shaft passing within said sleeve, said rolls being mounted on the shaft and spaced by collars, and a nut threading over each end 90 of said shaft to tighten and hold the shaft, sleeve, and disk for rotating together, said nuts being adapted to be unscrewed for changing wheels and rolls or to alter their spacing.

20. The combination with a stenciling machine and a shaft thereon, of a table arranged to be removably attached to said machine, a feed mechanism on said table, said feed mechanism comprising a shaft arranged 100 to be an extension of said machine shaft when said table is attached to said machine, and a clutch on said table shaft arranged to seize said machine shaft so that one shaft may drive the other.

21. The combination with a stenciling machine and a shaft thereon, of a table arranged to be removably attached to said machine, a feed mechanism on said table, a shaft in said feed mechanism, a clutch on 110 said feed shaft comprising a sleeve slidable thereon, a key on said machine shaft arranged to be engaged by said key to cause said shafts to revolve as a unit, a spring urging said sleeve to engage with said key, 115 and a latch to hold said sleeve.

22. The combination with a stenciling machine and a shaft thereon, of a table arranged to be removably attached to said machine, a key on said machine shaft, a feed 120 mechanism on said table, a shaft in said feed mechanism, and a sleeve slidable on said feed shaft comprising a beveled face and a slot arranged to lock with said key to cause said shafts to turn together.

23. In a stenciling machine, the combination 125 with a stencil holder, of a removable paper table comprising a feed mechanism,

gearing extending from said holder to a clutch, gearing extending from said clutch to said feed mechanism, and a member in said clutch arranged to prevent the seizing 5 of the clutch unless said feed mechanism is properly timed with reference to the stencil holder.

24. In a stenciling machine, the combination with a stencil holder, of a removable 10 paper table comprising a feed mechanism, means for gearing said feed mechanism to cause it to be operated from said stencil holder, and means causing said feed mechanism to automatically time itself correctly 15 with reference to said holder when the removed table is replaced.

25. In a stenciling machine, the combination with a stencil cylinder, of a removable 20 paper table comprising a feed mechanism, gearing connecting said cylinder to said feed mechanism, a spring clutch in said gearing, a latch holding said clutch released, and a member in said clutch arranged to prevent the seizing of said clutch when free from 25 said latch unless said feed mechanism is properly timed with reference to the stencil cylinder.

26. The combination with a paper table, of a reciprocating paper feeding device comprising an arm, a shaft rotatable on said 30 arm, abutments on said shaft, removable wheels, one on each side of said arm arranged to bear against said abutments, and means for locking each wheel against its 35 abutment.

27. The combination with a paper table, of a reciprocating paper feeding device comprising a central arm, a shaft rotatable on said arm, sleeves on said shaft, removable 40 wheels, one on each side of said arm arranged to bear against said sleeves, and sleeves arranged to lock said wheels against said first sleeves.

28. In a sheet feeding machine for a stenciling or printing machine, the combination 45 with a removable table for the sheets, a reciprocating carriage, and sheet feeding mechanism thereon, of a crank below said table revolving in a horizontal plane, a pit- 50 man connecting the crank to said carriage to reciprocate it, means to operate said crank, gearing connecting said printing machine to said carriage, a clutch in said gearing, and means whereby said clutch automatically 55 times the operations of said sheet feeding means to coöperate with said printing machine.

29. In a sheet feeding machine for a stenciling or printing machine, the combination 60 with a table for the sheets, a reciprocating carriage having sheet feeding mechanism thereon, and power transmitting means from said printing machine to operate the feeding machine, of means for attaching

said table to said stenciling machine without the aid of a tool and holding it in position when so attached, said means also permitting the detaching of the feeding machine without the aid of a tool for feeding the printing machine by hand, and clutch 70 members forming part of said transmitting means automatically brought into position to seize each other by so attaching said table.

30. In a sheet feeding machine for a stenciling or printing machine, the combination 75 with a table for the sheets, a reciprocating carriage having sheet feeding mechanism thereon, and power transmitting means from said printing machine to operate the feeding machine, of means for readily detach- 80 ing the feeding machine without the aid of a tool for feeding the printing machine by hand; said detaching means including a hook and pins for connecting both machine frames, and clutch mechanism comprising 85 members automatically brought into position for seizing each other for driving said transmission means.

31. In a sheet feeding machine for a stenciling or printing machine, the combination 90 with a table for the sheets, a reciprocating carriage having sheet feeding mechanism thereon, and power transmitting means from said printing machine to operate the feeding machine, of means for attaching said 95 feeding machine so that it may be readily detached for feeding the printing machine by hand; said means including a clutch mechanism comprising members automatically brought into position for seizing each 100 other for driving said transmission means.

32. In a sheet feeding machine for a hand fed stenciling or printing machine, said machines comprising drive shafts, the combination of a clutch for connecting the shafts of 105 said machines, and means for holding the frames of the machines together for attaching the feeding machine and bringing the members of said clutch automatically into position for seizing each other to render the 110 printing machine machine fed.

33. In a sheet feeding machine for a hand fed stenciling or printing machine, the combination with a table for the sheets, a reciprocating carriage with sheet feeding mechanism, and power transmitting means for connecting the mechanism of both machines, of means for readily attaching the feeding machine for feeding the printing machine; said attaching means including a clutch mechanism for said transmitting means, said clutch comprising members automatically 115 positioned for seizing each other.

34. In a sheet feeding machine for a stenciling or printing machine, the combination 125 with a table for the sheets, a reciprocating carriage with sheet feeding mechanism, and power transmitting means for connecting

the mechanism of both machines, of means for readily detaching the feeding machine for feeding the printing machine by hand; said detaching means including hooks and pins for locking both machine frames, and clutching means for said transmission means; said clutching means comprising members automatically brought into position for seizing each other.

35. The combination with a stenciling machine, of a detachable table arranged to feed

sheets to said machine, a leg for said table foldable to lie against the bottom thereof, a power carrier for said sheets comprising parts beneath said table, said parts lying close to said table, and mechanism lying close against the bottom of said table arranged to drive said carrier.

CHARLES GIBBS.
